US00D733558S

(12) **United States Design Patent**
Wyne(10) **Patent No.:** **US D733,558 S**
(45) **Date of Patent:** **** Jul. 7, 2015**(54) **METAL CAN ADAPTER**(71) Applicant: **Mark W. Wyne**, Chesterfield, MO (US)(72) Inventor: **Mark W. Wyne**, Chesterfield, MO (US)(73) Assignee: **Combined Manufacturing, Inc.**,
Wildwood, MO (US)(**) Term: **14 Years**(21) Appl. No.: **29/463,703**(22) Filed: **Feb. 13, 2014****Related U.S. Application Data**

(63) Continuation-in-part of application No. 29/442,096, filed on Dec. 5, 2012, now Pat. No. Des. 724,699.

(51) **LOC (10) Cl.** ..... **09-07**(52) **U.S. Cl.**USPC ..... **D9/436**; D9/447(58) **Field of Classification Search**

Primary Examiner — Robert M Spear*Assistant Examiner* — Darcey E Heflin*(74) Attorney, Agent, or Firm* — Paul M Denk**CLAIM**

The ornamental design for a metal can adapter, as shown and described.

DESCRIPTION

FIG. 1 is an isometric view of the metal can adapter of FIG. 9; FIG. 2 is a front view, the back view being a mirror image thereof;

FIG. 3 is a top plan view;

FIG. 4 is a bottom view;

FIG. 5 is an isometric view of the metal can adapter of FIG. 9, showing the rubber gasket insert removed from the adapter for clarity of disclosure;

FIG. 6 is a front view, the side views, and the back view being a mirror image thereof;

FIG. 7 is a top plan view;

FIG. 8 is a bottom view; and,

FIG. 9 is an isometric view of a metal can adapter showing my new design.

1 Claim, 2 Drawing Sheets(56)
